UNITED STATES PATENT OFFICE.

ANDREW MILLER, OF CANEY, KANSAS.

CURTAIN FASTENER.

Application filed February 12, 1924. Serial No. 692,357.

To all whom it may concern:

Be it known that I, ANDREW MILLER, a citizen of the United States, residing at Caney, in the county of Montgomery and State of Kansas, have invented certain new and useful Improvements in Curtain Fasteners, of which the following is a specification, reference being had to the accompanying drawings.

10 This invention relates to an improved curtain hanger and one object of the invention is to provide the hanger with an improved frame construction so that it may be placed in connection with windows of different 15 widths and be securely held in place, but at the same time permitted to be very easily removed when so desired.

Another object of the invention is to provide an improved construction of curtain 20 supporting rod which may be adjusted longitudinally according to the width of the window with which the frame is connected, thereby permitting this curtain supporting rod to be rotatably mounted between rearwardly extending arms of the frame.

Another object of the invention is to provide a frame which may be formed principally of metal tubes and rods positioned in telescoping relation to each other and to 30 provide an improved type of window frame engaging foot for the end portions of the curtain support.

This invention is illustrated in the accompanying drawings, wherein:

35 Figure 1 is a top plan view of the improved curtain support.

Figure 2 is a view showing an enlarged view of the curtain support with the support shown partially in top plan and partially 40 in longitudinal section.

Figure 3 is an enlarged perspective view of one of the attaching feet for connecting the curtain support with the window frame.

45 Figure 4 is an enlarged fragmentary perspective view of one end portion of the main tube used in forming the curtain support.

Figure 5 is an enlarged perspective view showing one end portion of the curtain carrying rod.

50 This improved curtain support is to be connected with a window frame so that lace curtains and the like may be supported in front of the window. The curtain support is provided with a main frame having a tube 1 which may be formed of any suitable

material and will have one end portion provided with a bayonet slot 2. The window frame engaging feet 3 and 4 are preferably formed of short lengths of tube having 60 their end portions flattened and split to provide legs 5 which extend in diverging relation towards their free ends and are bent to provide prongs 6 for fitting between the body portion of the window frame and corner blocks or the ends of a strip extending across the top of the window frame. By having the legs 5 provided with the prongs 6 for fitting between the body of the window frame and the corner blocks, the main frame 70 of the curtain support may be firmly held in place and will not be liable to slip loose as would be the case if the legs were simply provided with prongs intended to penetrate the sides of the window frame or corner 75 blocks.

Each of the window frame engaging feet 3 and 4 is to be connected with the tube 1 of the frame and, therefore, these feet 3 and 4 have been connected with rods 7 and 80 80 which extend into the end portions of the tube 1. The rod 8 of the foot 4 is shorter than the rod 7 of the foot 3 and has been provided with a side pin 9 which will pass into the bayonet slot and serve to very 85 securely hold the foot 4 in connection with the tube 1 when the rod is passed into the tube and then turned to position the pin in the angularly disposed inner end portion of the bayonet slot. The rod 7 of the foot 3 90 extends into the other end portion of the tube 1 and is provided with a tapered inner end portion having an eye 10 provided therein to receive the hook 11 at one end of the spring 12 which is positioned in the tube 95 1 intermediate its length and secured therein by a hook 13 engaged with a pin 14 extending transversely through the tube. There will, therefore, be seen that the rod 7 will be slidably mounted in the tube 1 and can 100 be drawn out of the tube when putting the curtain supporting frame in place in connection with the window frame. This frame under normal conditions will be of less length than the distance between the sides 105 of the smallest window frame with which it is intended to be used, thereby making it necessary to draw the rod 7 outwardly from the tube 1 when putting the curtain supporting frame in place. It will thus be 110 seen that when the rod is drawn outwardly from the tube and the prongs positioned for

passing between the body of the window frame or casing and the plaster of the wall about the window frames, the spring may draw the rod inwardly into the tube, and 5 when the prongs have been forced into proper position to engage the inner face of the window frame the curtain supporting frames will be firmly held in place.

10 The rod 15 which is to carry the curtain may be formed of the same type of metal from which the tube and rod 7 and 8 are formed and this rod is provided at its ends with pin extensions 16 and 17 for fitting into 15 openings 18 formed in the feet 3 and 4. With these pins positioned in the openings 18, the rod will be securely held in place and prevented from dropping out of the curtain supporting frame. The pin 16 may be 20 formed rigid with the rod 15 but the pin 17 will be preferably carried by a stem 19 which is threaded and may be screwed into or onto the end of the rod 15. It will thus be seen that by proper adjustment of the stem 19, the rod 15 may be lengthened and the pins 25 16 and 17 caused to fit properly into the openings 18 when the frame of the curtain support is expanded. It will further be noted that by this construction the frame of the curtain support may be put in place and 30 the curtain then slipped upon the rod 15. The pin 16 of this rod will then be inserted in one of the openings 18 and the rod then swung up into the proper position and the stem 19 unscrewed from the rod 15 a sufficient 35 distance to cause the pin 17 to enter the second opening 18. In order to ornament the end portions of the frame there has been provided ornamental heads 20 having threaded stems 21 which will be screwed into 40 threaded sockets or openings 22 formed in the feet 3 and 4. These ornamental heads may, if desired, be left off.

When this device is in use the rod 15 will 45 be removed from between the feet 3 and 4 and will be passed through a pocket formed in the upper portion of the curtain or the curtain may be simply passed about this rod and secured by pins. The frame will be put in place in connection with the window frame and the prongs 6 forced into place so 50 that the frame will be securely held in place. The curtain carrying rod 15 will then be put in place with the pins 16 and 17

fitting into the openings 18 and the curtain will be suspended in front of the window. 55 If it is desired to provide overdraperies, the overdraperies will be mounted upon the window engaging frame of this curtain hanger. When putting the overdraperies in place, the rod 8 will be removed from the 60 tube 1 and as soon as the overdraperies have been put in place, the rod 8 will be again inserted into the tube and turned to position the pin 9 in locking engagement with the tube at the inner end of the bayonet slot. 65 The overdraperies will then be slid along the tube and upon the feet 3 and 4 so that they will be properly positioned to give a good appearance. In case overdraperies are made use of it may be found necessary to 70 form slot openings in them so that the pins 16 and 17 may pass through the overdraperies and fit into the sockets 18. When it is desired to remove the curtains and curtain support, it is simply necessary to draw 75 the rod 7 outwardly and the support will be detached from the window frame.

What is claimed is:—

1. In a curtain support, a pair of angular brackets having flattened ends split longitudinally and flared to define attaching feet, the ends of the attaching feet being laterally extended and pointed to define prongs, each bracket further including an arm, the arms of the brackets extending toward each other and being arranged in alignment, a tubular member engaged upon said arms and constituting a longitudinal support, the intermediate portions of the brackets being formed with holes, a rod having reduced extensions seated within said holes, and said brackets being disposable against a wall outwardly of a window casing with the prongs forced between the wall and the casing. 85

2. In a curtain support, a bracket of tubular formation having one end laterally extended to define an arm and having its other end flattened, split and flared to define attaching portions, the ends of the attaching portions being laterally deflected and pointed whereby to be capable of engagement between a wall and a window casing. 90

In testimony whereof I hereunto affix my signature.

ANDREW MILLER.
